United States Patent Office

Des. 175,109
Patented July 12, 1955

175,109

COMB HOLDER

Fred W. Henry, Jamestown, N. Y.

Application February 16, 1954, Serial No. 29,049

Term of patent 7 years

(Cl. D86—10)

Fig. 1

Fig. 2

Fig. 3

Fig. 1 is a front elevational view of a comb holder showing my new design;

Fig. 2 is a top plan view; and

Fig. 3 is a side or end elevational view.

I claim:

The ornamental design for a comb holder, substantially as shown.
